UNITED STATES PATENT OFFICE.

JOHN ZILIUS, OF HUNTINGDON, PENNSYLVANIA.

DEVICE FOR REPAIRING CAR-COUPINGS.

1,073,383.

Specification of Letters Patent. Patented Sept. 16, 1913.

Application filed December 12, 1912. Serial No. 736,261.

To all whom it may concern:

Be it known that I, JOHN ZILIUS, a citizen of the United States, residing at Huntingdon, in the county of Huntingdon and State 5 of Pennsylvania, have invented certain new and useful Improvements in Devices for Repairing Car-Couplers; and I do hereby declare the following to be a full, clear, and exact description of the invention, such as will 10 enable others skilled in the art to which it appertains to make and use the same.

This invention relates to a device for repairing car couplers, and it more particularly relates to an emergency repair coupler 15 device which is adapted for adjustment to fit draw-bars of different sizes.

An object of the invention is to provide an improved device of this character with an invertible slide element for holding the 20 repair member or auxiliary coupler-head in fixed position on the draw-bar.

Another object of the invention is to provide a repair element of this character which may be applied on coupler-heads of 25 any of the standard makes, even though said coupler-heads may be broken to such an extent that only the middle portion thereof remains intact.

Another object of the invention is to provide a repair member of this character which will positively hold and support the broken coupler-head, in case the draw-bar which carries the same should become disconnected from the car which carries it.

Another object of the invention is to provide a device of this character which may be interchangeably connected with all of the 35 principal automatic couplers in use.

A still further object is to provide a device of this character which is of maximum strength, consistent with minimum weight, and of maximum efficiency, consistent with minimum cost, and withal thoroughly efficient.

With these objects in view the invention consists in the improved construction, arrangement and combination of parts of a device of the character specified which will be hereinafter fully described and afterward 45 specifically claimed.

In the accompanying drawings, Figure 1 is a bottom plan view of a broken coupler-head having my improved repair head seat-

ed thereon. Fig. 2 is a vertical sectional view on line 2—2 of Fig. 1. Fig. 3 is a vertical sectional view on line 3—3 of Fig. 1. Fig. 4 is a detail view, in elevation, of the 55 100 150 200 250 300 350 400 450 500 550 600 650 700 750 800 850 900 950 1000 1050 1100 1150 1200 1250 1300 1350 1400 1450 1500 1550 1600 1650 1700 1750 and deep to receive the largest size of draw-bars, in the present instance seven inches wide. On the rear wall is formed these lugs 16 which depend therefrom, and said rear wall is recessed centrally, as an extension of the recess between the lugs. The lugs and rear wall are provided with grooves 27 which extend from the bottom to the top of the recess and of the lugs 16, and said lugs 5 are each provided with a vertical slot 28 which communicates with the respective grooves 27. Within the grooves 27 are seated the lugs or lateral extensions 29 of the yoke 30. This yoke is substantially U-shaped, 10 and its sides or arms 31 are slotted at 32, between the lugs 29, while its medial bar is grooved at 33. When the yoke 30 is placed in the position shown in Fig. 3, the draw-bar 11 fits snugly within the recess of the 15 rear wall, while the yoke 30 is in the position shown in Fig. 4, and the wedge-key 35 is seated in the slots 28 and 32 and groove 34, so as to hold the yoke up against the draw-bar 11. However, when a small draw-bar 20 is to be fitted with my improved auxiliary coupler-head, the yoke 30 is inverted, as shown in Fig. 6, so that the arms 31 embrace the draw-bar 12 and fill the space between said draw-bar and the adjacent portions of 25 the rear wall, and thereby prevent undue lateral movement of said draw-bar and said rear wall. The key 35 is provided with a plurality of apertures 36, into either of which the key 37 (see Fig. 7), may be inserted, so as to hold said key in adjusted 30 position. The key preferably comprises semicylindrical bars 38 having their adjacent ends connected by a bow-spring 39, so that the bars 38 may be easily pressed into 35 contiguity, so as to be inserted through one of the holes 36, whereupon the bow-spring tends to force the bars 38 apart so as to bind them by friction within the aperture. 40 It is well known that automatic couplers 45 of ordinary construction are each provided with a vertical shoulder or abutment 40; and my auxiliary coupler-head is therefore provided with the rear wall 20 of sufficient height, above the draw-bar, to have full engagement with the abutment 40, so that if any of the abutment remains (not broken off), the rear wall 20 will engage with the abutment 40, while the yoke and wedge-key 50 coöperate with the lugs 16 for holding said rear wall and said abutment in engagement. 55 In applying the device, the auxiliary head is lowered into position upon the broken coupler-head, as shown in Figs. 1 and 2, and the yoke 30 is then placed with the lugs 60 29 in the grooves 27 and is slid up against the draw-bar; it being understood that the yoke is placed in the position shown in Fig. 3 or in the position shown in Fig. 6, according to whether the draw-bar is five by seven 65 or five by five inches in cross section. The

wedge 35 is then placed in the slot 28 and in the slot 32 or groove 33, as in Figs. 3 and 6, respectively, whereupon the key 37 is placed, as described, for retaining the key in its adjusted position. 70

The cover 21 is provided with an aperture 21' through which a knuckle lock may be inserted, when the device is employed with a coupler which embodies such knuckle lock. 75

From the foregoing, it will be seen that 75 I have provided an auxiliary coupler-head or temporary repair device which is fully capable of attaining the foregoing objects, in a thoroughly practical and efficient manner. 80

I do not limit my invention to the exact details of construction, combination and arrangement of parts, as herewith illustrated and described, but my invention may only be limited by a reasonable interpretation of 85 the claims. 85

I claim:—

1. In a device for repairing car couplers, an auxiliary coupler-head comprising a housing having a forwardly disposed knuckle and having a recessed rear wall with securing lugs depending therefrom and provided with vertical grooves in the depending lugs and rear walls, said securing lugs being provided with slots communicating with the vertical grooves, and a yoke having lateral extensions adapted to be slid in the vertical grooves and seated against the under side of a draw-bar of an ordinary coupler, said yoke being provided with slots 90 between said vertical grooves, and a wedge-key movably fitted in said slots of the yoke and the depending lugs for securing the yoke in adjusted position. 95

2. In a device for repairing car couplers, 105 an auxiliary coupler-head comprising a forwardly disposed knuckle and housing and having a rear wall adapted to engage with the vertical shoulder or abutment of an ordinary car coupler, securing lugs depending 110 from the rear wall and having slots therethrough, a yoke having slots therethrough and adapted to be inserted between said securing lugs in either upright or inverted position, a wedge-key adapted to be seated 115 in the slots of the depending lugs and yoke in either position of the yoke for securing the yoke in adjusted position.

3. In a device for repairing car couplers, 120 a housing having a forwardly disposed knuckle and having a rear wall with depending lugs thereon, a substantially U-shaped yoke adapted to be inserted between the depending lugs in either upright or inverted position for retaining the coupler-head in 125 proper position relative to draw-bars of different sizes, and a wedge-key for securing the yoke in either adjusted position.

4. In a device for repairing car couplers, 130 an auxiliary coupler-head having a rear wall

and having spaced lugs depending from the rear wall for receiving therebetween coupler draw-bars of different sizes, and a substantially U-shaped yoke adapted to be fitted between the securing lugs in either of two alternative positions, so that the arms of the U-shaped yoke may embrace the draw-bars of relatively small size for securing said draw-bar in the same position relative to the

auxiliary coupler-head as that of a larger 10 sized draw-bar.

In testimony whereof I have signed my name to this specification in the presence of two subscribing witnesses.

JOHN ZILIUS.
